UNITED STATES PATENT OFFICE.

ALFRED MEHLHORN, OF DIETRICHSDORF, GERMANY.

WATER-TUBE STEAM-BOILER.

SPECIFICATION forming part of Letters Patent No. 707,440, dated August 19, 1902.

Application filed March 28, 1902. Serial No. 100,467. (No model.)

To all whom it may concern:

Be it known that I, ALFRED MEHLHORN, a subject of the Emperor of Germany, residing at 11 Schwentinestrasse, Dietrichsdorf, near 5 Kiel, Germany, (whose post-office address is the same,) have invented certain new and useful Improvements in Water-Tube Steam-Boilers; and I do hereby declare the following to be a full, clear, and exact description of the 10 invention, such as will enable others skilled in the art to which it appertains to make and use the same.

This invention relates to a water-tube boiler by means of which an effect approximate 15 to that of a counter-current is obtained, and therewith intense development of heat and considerable utilization of the heating-gases.

In the accompanying drawings, Figure 1 is 20 a transverse section of a boiler constructed according to this invention. Fig. 2 is a side elevation on a smaller scale, and Figs. 3 and 4 are sections of modified forms of boilers constructed on the same principle.

25 In the form shown in Fig. 1 the steam-boiler consists of the lower drum divided by a partition into two parts *a* and *e*, the upper drum *b* *f* with the partition *b'* and the lower drum *i*. Both of the lower drums are connected with 30 the upper drum by the nests of tubes I, II, and III, as well as by the down-pipes *c d g h*.

The compartments *a e b f*, formed by the 35 partitions in the drums, may be replaced by four separate drums. (See Fig. 3.)

30 The external tubes of the groups I, II, and III are arranged close together to form walls. In order to provide passages for the heating-gases, the pipes forming the walls may be bent at the top and bottom. However, inserted walls may also be used and which are 40 likewise correspondingly broken away.

Fig. 1 represents the boiler in cross-section and at the same time illustrates the grouping arrangement of two or more drums, while 45 Fig. 2 is a side view of the boiler.

Figs. 3 and 4 represent modifications of the original forms of construction in so far that in the case of Fig. 3 special drums are arranged instead of the separate chambers 50 formed by partitions in the drums, and in Fig. 4 the upper drum is divided into three compartments instead of two, while in both

cases series of tubes forming walls are replaced by inserted walls.

From Fig. 2 it will be seen that the down-pipes are outside the boiler masonry—that is, not within range of the fire and the heating-gases—whereby a downward movement of the water therein is assured.

The feed-water enters the lower drum *a*, 60 Fig. 1, and on being heated passes into the upper drum *b* through the heating-tubes I. The down-pipe *c* serves to maintain the circulation of water in the part of the boiler indicated under *a* I *b*, so that in case the 65 feed be interrupted there can be no lack of water in the tubes I. As the feed-water introduced into *a* is only partially vaporized, it collects in *b* and is conveyed through the down-pipe *d* into the lower compartment or 70 drum *e*, whence it rises, passing through the heating-tubes II into the upper part of the boiler and principal steam-chamber *f*. The down-pipe *g* is employed for keeping up the circulation in the boiler-compartments *e II f*. 75 From the pipe *g* the pipe *h* branches off, through which water is conveyed to the nest of tubes III, which connects the lower drum *i* with the upper drum *f*. The down-pipes *g* and *h* may be arranged singly and quite 80 separately—for instance, *h* may run direct from *f* to *i*. The feed-water, however, may be introduced as required into the upper or lower boiler.

The heating-gases coming from the fire-bars 85 *r* first sweep along the nest of tubes III, then downward over the tubes II and the chamber IV, and downward again over the tubes I, whereupon they enter the flue.

Owing to the circumstance that the warmest 90 heating-gases are brought into contact with the warmest bodies of water and then by stages with the cooler bodies of water and in a direction contrary to that of the flow of the water an effect approximate to the action 95 of a counter-current is obtained, which in consequence insures the heating-gases being better utilized than is the case in other tubular boilers.

A further advantage as compared with 100 other systems consists in the small radiating external surfaces of the boilers under the group arrangement, Fig. 1. The upper drum may also be divided into several parts by

partitions, (see Fig. 4,) or instead of a single upper drum several lying separate from one another may be employed. (See Fig. 3.) The further construction as regards the down-
5 pipes and groups of heating-tubes is the same in this case, the latter being simply adapted to the actual lower or upper drum employed. The effect thereby obtained is precisely the same, and it is of no consequence as regards
10 the value of the invention whether insertion-walls are employed or series of tubes forming walls, as indicated in Figs. 1 and 2.

The operation of the boiler as in Figs. 3 and 4 is to be seen from the drawings and
15 requires no further explanation.

What I claim, and desire to secure by Letters Patent, is—

1. In a steam-generator, the combination with lower drums or compartments *a*, *e*, *i*,
20 and upper drums or compartments *b*, *f*, of a series of heating-tubes I, connecting the compartments *a*, *b*, a series of heating-tubes II connecting the compartments *e*, *f*, a series of heating-tubes III connecting the compartments *f*, *i*; pipes *c*, *d*, connecting compartments *a*, *e*, with compartment *b*; pipe *g* connecting compartments *e*, *f*, and pipe *h* connecting the compartment *i* and pipe *g*, the various series of heating-tubes being so arranged that the series III will be acted upon
25
30

first by the heating-gases, and the other series II, I, in succession thereafter and said heating-gases caused to take a direction contrary to that of the water.

2. In a steam-generator, the combination 35 with the masonry, of lower drums or compartments *a*, *e*, *i*, and upper drums or compartments *b*, *f*, arranged within the space enclosed by the masonry, a series of heating-tubes I connecting the compartments *a*, *b*, a 40 series of heating-tubes II connecting the compartments *e*, *f*, a series of heating-tubes III connecting the compartments *f*, *i*; pipes *c*, *d*, connecting compartments *a*, *e*, with compartment *b*; pipe *g*, connecting compartments 45 *e*, *f*, and pipe *h* connecting the compartment *i* and pipe *g*, said pipes *c*, *d*, *g*, *h*, being arranged outside of the masonry, the various series of heating-tubes I, II, III, being so arranged that the series III will be acted upon 50 first by the heating-gases, and the other series II I in succession thereafter, and said heating-gases being caused to take a direction contrary to that of the water.

In testimony whereof I affix my signature 55 in presence of two witnesses.

ALFRED MEHLHORN.

Witnesses:

JULIUS RÖYKE,
MARTIN SCHMIETAN.
